**COMBINED MAGAZINE RACK AND STAND FOR
A ROOM AIR CONDITIONER OR THE LIKE**

Harold G. Anderson, Cincinnati, Ohio, assignor to The Brunhoff Manufacturing Company, Cincinnati, Ohio, a corporation of Ohio

Application December 17, 1956, Serial No. 44,232

Term of patent 14 years

(Cl. D62—4)

Figure 1 is a perspective view of a combined magazine rack and stand for a room air conditioner or the like showing my new design.

Figure 2 is an end elevation thereof.

Figure 3 is a rear elevation thereof.

Figure 4 is an enlarged fragmentary sectional view taken along the line 4—4 of Figure 1.

The design detail, shown fragmentarily for convenience of illustration only, covers the entire surface of the shelf element and all surfaces of the magazine rack element, except for the border strip along the upturned front edge thereof, as indicated in the figures of the drawings.

I claim:

The ornamental design for a combined magazine rack and stand for a room air conditioner or the like, substantially as shown and described.
